[57] CLAIM

The ornamental design for a dishwasher control keypad, as shown and described.

DESCRIPTION

FIG. 1 shows a front view of the dishwasher control keypad; FIG. 2 shows a side view of the dishwasher control keypad; FIG. 3 shows a top view; and, FIG. 4 is a front right perspective view.

The characteristic feature of the design resides in the button layout and pattern and the shape of the front panel all as shown in FIG. 1.
